SAFETY LOCK PROTECTOR

Samuel Freedman, New York, N. Y.

Application June 22, 1939, Serial No. 280,473

4 Claims. (Cl. 292—297)

This invention relates to new and useful improvements in a safety lock device.

More specifically, the invention proposes the construction of a safety lock device characterized by a flat member adapted to be inserted between the free edge of a door element and the adjacent edge of a door jamb and provided with a means for holding the door in a closed position regardless of the direction in which it swings.

10 Still further it is proposed to provide the flat member with a lateral projection at one end engageable against either the door element or the jamb element for preventing the flat member from being pushed from between the adjacent faces of the door element and the jamb element.

Still further it is proposed to provide an arm pivotally mounted on the other end of the flat member on the side opposed to the projection and engageable against the opposite element to the 20 one engaged by the projection to prevent the door from being opened when the lock device is in position.

Still further it is proposed to provide the free end of the arm with a head adjustably mounted thereon to permit the device to be properly adjusted to accommodate doors of different thicknesses.

A further object of this invention is to construct a lock device having an arm constructed 30 of telescopic sections and to provide a means for holding the sections extended to various degrees.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a cross sectional view of a door having a safety lock device according to this invention associated therewith.

Fig. 2 is a perspective view of the safety lock device per se.

Fig. 3 is a partial elevational view of a lock device constructed according to a modification of the invention and having a portion thereof broken away to reveal interior construction.

50 Fig. 4 is an enlarged detailed view of a portion of Fig. 3.

Fig. 5 is a view looking in the direction of the line 5—5 of Fig. 3.

The safety lock device, according to this invention, is to be used in combination with a

door element 10 hingedly mounted relative to a jamb element 11. The lock device includes a flat member 12 adapted to be rested upon the edge portion of the jamb element 11 and to be passed between the adjacent faces of the jamb element and the door element as clearly shown in Fig. 1. One side of the flat member 12 is formed with a lateral projection 12^a near one end thereof and is engageable against either of the elements for preventing the flat member 10 from being pushed from between the adjacent faces of the elements in the closed position of the door element 10.

An arm 13 is pivotally mounted at the other end of the flat member 12 on the side opposed to the lateral projection 12^a. A pin 14 passes through the overlapping portions of the arm 13 and flat member 12 and constitutes the means for pivotally supporting the arm upon the flat member. The arm 13 is arranged upon the end of the flat member in such a manner that it is adapted to swing in a plane adjacent the plane of the flat member.

A head 15 is adjustably mounted upon the free end of the arm 13 and is adapted to abut against one of the elements 10 or 11 for holding the door against swinging. The adjustable mounting of the head 15 comprises a screw 16 fixedly attached to the inner face of the head 15 and threaded into an opening 17 formed in the adjacent end of the arm 13. When the arm 13 is pivoted to a position illustrated by the dot and dash lines 13' in Fig. 1 the head 15 may be extended by rotating it to cause it to engage tightly against either of the elements 10 or 11, as shown by the dot and dash lines 15', which in turn holds the projection 12^a tightly against the other of the elements 10 or 11.

The operation of this device is as follows:

For locking a door against hinging the door element is first moved to an open position and the face of the flat member 12 having the projection 12^a is rested against the jamb element 11 with the projection 12^a engaging against the outer face of the jamb element 11. The door element 10 is then swung to a closed position with the flat member disposed between the adjacent edges of the jamb element 11 and the door element 10. The arm 13 is then swung from the full line position in Fig. 1 to the dot and dash position in Fig. 1 and the head 15 is extended therefrom to rigidly bear against the inner face of the door element 10.

If the door element swings in the opposite direction from that shown in Fig. 1 the door may

be held in a closed position by engaging the projection 12^a against the outer face of the door element 10, and the head against the inner face of the jamb element 11. In other words, if the door swings in the opposite direction, the position of the parts 12^a and 15 are reversed.

According to the modification of the invention shown in Figs. 3-5, the arm 13 is constructed from separate sections 13^a and 13^b telescopically engaged one within the other. The section 13^a is pivotally supported on the end of the flat member 12 by means of the pin 14 passing therethrough.

A means is provided for holding the section 13^b extended to various degrees upon the section 13^a. This means comprises a plurality of openings 18 formed along one of the faces of the section 13^a and alignable with an opening 19 formed in the adjacent face of the section 13^b. A peg 20 is adapted to be passed through the opening 19 and the adjacent aligned opening 18 for holding the sections 13^a and 13^b together as a rigid unit. The free end of the section 13^a is adapted to engage into a hollow 21 formed in the section 13^b. The hollow 21 extends only partially throughout the length of the section 13^b and a second hollow 22 is formed in the section 13^b at the end of the hollow 21.

A block 23 is slidably engaged within the hollow 22 and the screw 16 mounted upon the head 15 threadedly engages into an opening 17 formed in the block 23. The adjustment between the telescopic sections 13^a and 13^b is a coarse one permitting spaced adjustments of about $\frac{1}{8}$ of an inch, depending on the space between the openings 18. The use of the head 15 and the screw 16 permits finer adjustments to compensate for the distance between the openings 18 to permit the head 15 to be tightly engaged against the adjacent face of either of the elements.

A latch device is provided for holding the arm 19 in a fixed position when the lock device is in operation and consists of a latch member 24 having one of its ends securely attached to the extended end of the peg 20. The other end of the latch element 24 extends through an opening 25 formed on the side of the hollow 22 and has its ends 24^a bent to extend into the hollow 22. The rear face of the block 23 is formed with an opening 26 into which the end 24^a of the lock device 24 is adapted to be engaged when the block 23 is moved to its rear position. The screw 16 freely passes through the outer wall of the section 13^b so that the block 23 may be moved longitudinally of the section 13^b to engage and disengage the openings 26 from the end 24^a of the latch member 24.

The latch member 24 is constructed from a strip of rigid material and when the end 24^a thereof engages into the opening 26, the peg 20 will be rigidly maintained in position within the openings 18 and 19. A leaf spring 27 has one of its ends securely attached to one of the faces of the section 13^b and the other of its ends engaging against the latch member 24 for urging it towards the section 13^b to cause the peg 20 to be engaged into the openings 19 and 18.

The operation of this form of the invention is as follows:

The lock device is associated with the jamb element and the door element in a manner similar to that described relative to the previous form of the invention, but when the arm 13 is swung to a position adjacent the flat member 12 the section 13^b may be extended from the

section 13^a to bring the head 15 as close to the adjacent face of the associated element permitting the head 15 to then be moved away from the section 13^b to engage it tightly against the element to maintain the door elements in its closed position. In other respects this form of the invention is similar to the previous form.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A safety lock device for a door element hingedly mounted to a jamb element, comprising a flat member adapted to rest on the jamb element and pass between said elements and having a lateral projection at one end portion engageable against one of said elements, an arm pivotally mounted at one end on the other end portion of said flat member so as to swing in a parallel plane adjacent the plane of said flat member, and a head adjustably mounted on the free end of said arm longitudinally thereof and adapted to abut one of said elements to hold the door element from hinging, said arm being constructed of separate sections telescopically engaged one within the other, and a means for holding said sections in various extended positions.

2. A safety lock device for a door element hingedly mounted to a jamb element, comprising a flat member adapted to rest on the jamb element and pass between said elements and having a lateral projection at one end portion engageable against one of said elements, an arm pivotally mounted at one end on the other end portion of said flat member so as to swing in a parallel plane adjacent the plane of said flat member, and a head adjustably mounted on the free end of said arm longitudinally thereof and adapted to abut one of said elements to hold the door element from hinging, said arm being constructed of separate sections telescopically engaged one within the other, and a means for holding said sections in various extended positions.

3. A safety lock device for a door element hingedly mounted to a jamb element, comprising a flat member adapted to rest on the jamb element and pass between said elements and having a lateral projection at one end portion engageable against one of said elements, an arm pivotally mounted at one end on the other end portion of said flat member so as to swing in a parallel plane adjacent the plane of said flat member, and a head adjustably mounted on the free end of said arm longitudinally thereof and adapted to abut one of said elements to hold the door element from hinging, said arm being constructed of separate sections telescopically engaged one within the other, and a means for holding said sections in various extended positions, said means comprising a peg engageable through an opening formed in one of said sections and selectively engageable with one of a plurality of openings formed in the other section, and a latch means for rigidly maintaining said peg in position within said openings.

3. A safety lock device for a door element hingedly mounted to a jamb element, comprising a flat member adapted to rest on the jamb element and pass between said elements and having a lateral projection at one end portion engageable against one of said elements, an arm pivotally mounted at one end on the other end portion of said flat member so as to swing in a parallel plane adjacent the plane of said flat member, and a head adjustably mounted on the free end of said arm longitudinally thereof and adapted to abut one of said elements to hold the door element from hinging, said arm being constructed of separate sections telescopically engaged one within the other, and a means for holding said sections in various extended positions, said means comprising a peg engageable through an opening formed in one of said sections and selectively engageable with one of a plurality of openings

- formed in the other section, and a latch means for rigidly maintaining said peg in position within said openings, said latch means comprising a slidably mounted block mounted within a hollow formed in a portion of one of said sections and adjustably supporting said head, a latch member extending along the outside of said sections and having one of its ends fixedly attached to the outer end of said peg, said latch element 5 having the other of its ends extended into said hollow and engageable into an opening formed in the rear face of said block for holding said end in position within said hollow and for holding said peg in position within said openings.
- 10 15 20 25 4. A safety lock device for a door element hingedly mounted to a jamb element, comprising a flat member adapted to rest on the jamb element and pass between said elements and having a lateral projection at one end portion engageable against one of said elements, an arm pivotally mounted at one end on the other end portion of said flat member so as to swing in a parallel plane adjacent the plane of said flat member, and a head adjustably mounted on the free end 20 25 of said arm longitudinally thereof and adapted to abut one of said elements to hold the door element from hinging, said arm being constructed of separate sections telescopically engaged one within the other, and a means for holding said sections in various extended positions, said means comprising a peg engageable through an opening formed in one of said sections and selectively engageable with one of a plurality of openings formed in the other section, and a latch means for rigidly maintaining said peg in position within said openings, said latch means comprising a slidably mounted block mounted within a hollow formed in a portion of one of said sections and adjustably supporting said head, a latch member extending along the outside of said sections and having one of its ends fixedly attached to the outer end of said peg, said latch element having the other of its ends extended into said hollow and engageable into an opening formed in the rear face of said block for holding said end in position within said hollow and for holding said peg in position within said openings, and a leaf spring having one of its ends attached to a portion of said arm and the other of its ends engaging against said latch element for assisting in maintaining it in a fixed position.

SAMUEL FREEDMAN.
